UNITED STATES PATENT OFFICE.

WILLIAM D. REDRUP, OF HUNTINGTON, INDIANA, ASSIGNOR TO THE MAJESTIC COMPANY, OF HUNTINGTON, INDIANA, A CORPORATION OF INDIANA.

DESIGN FOR A BOOK END.

Application filed March 22, 1928. Serial No. 25,959. Term of patent 14 years.

To all whom it may concern:

Be it known that I, WILLIAM D. REDRUP, a citizen of the United States, residing at Huntington, in the county of Huntington and State of Indiana, have invented a new, original, and ornamental Design for Book Ends, of which the following is a specification, reference being had to the accompanying drawing, forming a part thereof.

In the drawing, Figure 1 is a front elevation and Figure 2 is a side edge elevation of a book end, showing my new design.

I claim:

The ornamental design for a book end, substantially as shown.

WILLIAM D. REDRUP.
